United States Patent Office

Des. 186,146
Patented Sept. 15, 1959

186,146

BASE FOR A PEN OR THE LIKE

William S. Sherman, Chicago, Ill., assignor to Cory Corporation, Chicago, Ill., a corporation of Delaware

Application August 14, 1958, Serial No. 52,208

Term of patent 14 years

(Cl. D74—1)

Fig. 2 is a side elevational view of the same;

Fig. 3 is a top plan view of the same; and

Fig. 4 is a perspective view thereof.

The dotted line showing of a pen in Fig. 4 is for illustrative purposes only.

I claim:

The ornamental design for a base for a pen or the like, substantially as shown and described.
